UNITED STATES PATENT OFFICE

2,664,729

HYDROCARBON FUEL BURNER

Carl Bramming, Anderson, Ind., assignor to
Aladdin Industries, Incorporated, Nashville,
Tenn., a corporation of Illinois

Application August 17, 1950, Serial No. 180,062

6 Claims. (Cl. 67—41)

1

My invention relates to an improved hydrocarbon fuel burner having improved control mechanism for starting, running, or shutting off the burner, an improved pump construction, and an improved chimney lifting mechanism.

In one method of starting a hydrocarbon fuel burner of the vapor type, the fuel is delivered to the burner in an atomized condition and is then ignited. The resultant flame heats the generator tube (which is adjacent the burner) and after a short time, causes the vaporization of further fuel reaching the burner. When this condition of operation is achieved, fuel in liquid form is delivered to the generator tube which vaporizes the fuel for normal burner operation with vaporized fuel.

In accordance with the present invention, means is provided to control the burner for either of the three operating conditions (start, run, and shut off) in a positive manner, yet in a way that gives rise to positive opening and closing valve motions. Moreover, the necessary control is achieved in a simple, inexpensive, and reliable mechanism actuated by a rotatable handle having three equally spaced angular positions where it is releasably held for operation. The resultant simple control is particularly effective for use by unskilled persons who frequently fail to understand the operation of the devices of this type now in use and misuse them.

It is therefore a general object of the present invention to provide an improved control mechanism to deliver liquid hydrocarbon fuel to a vapor type burner and characterized by a high degree of simplicity in adjustment to start, run, and shut-off conditions.

Another object of the present invention is to provide a three position control mechanism to deliver liquid hydrocarbon fuel to a vapor type burner that is simple and inexpensive in construction and reliable in operation and is suitable for application to hydrocarbon fuel burners of many types.

Still another object of the present invention is to provide an improved three-position control mechanism for a hydrocarbon fuel burner of the pressure type that includes direct-connected elements extending into the liquid fuel and defines an outlet passage suitable for direct connection to the generator of the burner.

It is another object of the present invention to provide an improved hydrocarbon fuel burner of the pressure type wherein the pump required to provide initial fuel pressure is formed unitarily

2

with the filling cap and discharges to a space that is free from fuel.

Yet another object of the present invention is to provide an improved hydrocarbon fuel burner having a chimney lifting mechanism to elevate the chimney for starting.

The novel features which I believe to be characteristic of my invention are set forth with particularity in the appended claims. My invention itself, both as to its organization and method of operation together with further objects and advantages thereof, will best be understood by reference to the following description taken in connection with the accompanying drawings, in which:

Figure 1 is an axial cross-sectional view with parts in elevation of a gasoline pressure lantern equipped with the control mechanism of the present invention and showing parts in elevation;

20 Figure 2 is a fragmentary cross-sectional view along axis 2—2, Figure 1;

Figure 3 is a fragmentary cross-sectional view along axis 3—3, Figure 2;

25 Figure 4 is a fragmentary cross-sectional view along axis 4—4, Figure 1;

Figure 5 is an enlarged fragmentary cross-sectional view of the nozzle portion of the lantern of Figure 1;

30 Figure 6 is a fragmentary enlarged cross-sectional view through axis 6—6, Figure 1; and

Figure 7 is a fragmentary view of the hood of the lantern of Figure 1 in the elevated, igniting position.

Referring now to Figure 1, there is shown a gasoline pressure lantern having a fuel tank 1; a control mechanism 2, a generator tube 3, and a burner 4. A mantle 5 is supported by the burner 4 and is heated to incandescence by the burning gasoline vapor. A chimney 6 surrounds the generator, burner and mantle, and a hood 7 extends over the top of the unit. In operation, gasoline under pressure in the tank 1 is forced upward into the generator tube 3 where it is vaporized. It thereafter travels through nozzle housing 8 and enters the mixing tube 9 where it mixes with air in correct proportion for combustion and is supplied to the burner 4. The vapor-air mixture then burns at the end of the mantle mounting 10 to heat the mantle 5.

50 As will be described in further detail hereafter, the normal operation described above is initiated by preliminarily heating the generator tube 3 to vaporize the gasoline or other fuel. This is accomplished by delivering atomized fuel through the generator 3 to the burner 4 for the prelim-

inary heating period, which fuel, when ignited, furnishes the necessary heating flame.

The fuel tank, indicated generally at 1, consists of a generally cup-shaped top member 11 which receives the concave bottom 12 at its open lower end. The top 11 has an indented ring 13 of generally semi-circular cross-section extending around its bottom portion. The bottom 12 has an upturned side portion 14 which mates with and extends around the portion of the top 11 below ring 13. The portion of side 14 extending above the lower margin of ring 13 is peened over as shown and a braze bead 15 formed about the resultant edge to secure the bottom 12 in a sealed relation to top 11.

The top 11 has a circular hole 16 in its top conical face. This hole receives the sleeve 17 which snugly fits therein and is sealed thereto by a bead of solder or the like to form a non-leaking joint. The sleeve 17 has external threads 18 near its upper edge which mate with and receive the corresponding threads 19 of the pump-supporting top cap 20.

The top cap 20 is attached to the washer 21 which has an annular groove 22 which fits snugly over the upper edge of the sleeve 17. A packing washer or gasket 23 is sandwiched between these parts to form a tight seal. On its inner edge, the washer 21 is annexed to the depending pump tube 24 which extends into the tank 1. This washer receives cap 25 at its bottom end, which cap has an air outlet port 26 and a one way valve 27. Pipe 28 extends from the outlet of sleeve 17 to deliver air direct to the space immediately beneath washer 21.

As shown in the drawing, the valve 27 includes a movable valve member 29 which is urged to a seated position on the seat 30. When the air pressure in the pipe 24 is increased substantially above that in the pipe 28 (due to downward stroke of the plunger 32 which carries piston 32a) air is forced into pipe 28 and the pressure in the space below washer 21 and hence the pressure in the tank 1 is increased.

Plunger 32 is actuated by up and down strokes imparted to the handle 33 and is urged downwardly by the spring 34 which, at the upper limits of plunger movement, bottoms against top cap 20.

It will be observed that the pump forces air directly into the space immediately below the washer 21. This has the advantage of placing air at the point at which cap 20 is attached so that leakage, if it occurs, is air leakage and not gasoline leakage. Moreover, this construction minimizes the opportunity for gasoline to gain access to the valve 27 or the pump.

It will be noted that the pump construction utilizing the cap 20 and washer 21 may be removed from the tank 1 by unscrewing cap 20, thereby providing an opening through the sleeve 17 for refueling the tank 1. Consequently, it is unnecessary to provide a separate tank-filling opening.

The top part 11 of the tank 1 has a centrally disposed circular aperture 35 which snugly receives the sleeve 36. This sleeve is soldered or otherwise secured to the tank 1 to define a fluid tight seal. In turn, it receives the lower portion 37 of the housing 38, this part being removably held in sealed relation to the sleeve 36. In the structure shown, this sealed relation is established by complementary threads on these parts which force the seating parts to a snug fit when housing 38 is rotated relative to the sleeve 36.

A pair of pipes 39 and 40 depend from the hous-

ing 38 and extend into the fluid fuel in the tank 1. As seen best in Figure 2, these pipes are secured to the ported connectors 41 and 42 which are in turn threadedly secured to the bottom portion 37 of the housing 38.

The central portion of the housing 38 has a circular horizontal bore 43. A pair of passages 44 and 45 extend downwardly from bore 43 and at their lower ends expand into the chambers 46 and 47, respectively, these chambers terminating in the internally threaded portions of housing 38 which receive the connectors 41 and 42.

Intermediate the passages 44 and 45, the housing 38 has an upwardly extending passage 48, which passage has a slightly enlarged portion 49 at its upper end to receive the generator tube 3. A cap 50 is threadedly secured to the upper end of the housing 38 and overlays annular wedge 51. As the cap is tightened, the wedge 51 is driven down against pipe 3 to force it to a snug fluid tight fit in the housing 38.

At its lower portions, the generator pipe 3 receives glass wool material 52, this material being held in position by the screen 53, which seats against the constructed portion 54 of the tube 3. At its upper end, the tube 3 is received in the nozzle housing 8 which has a T-shaped bore 56—57—58, Figure 5, portion 56 being in registry with the tube 3. The vertical bore 58 threadedly receives the nozzle sleeve 59 at its lower end, which nozzle sleeve in turn threadedly receives the nozzle tip 60 which has a very small port 61 through which the fuel passes into the mixing tube 9.

The mixing tube 9 is threadedly secured to the bottom margin of the skirt 62 formed on the nozzle housing 8. This skirt surrounds the nozzle opening or port 61 and behind the nozzle port (as seen in Figure 1) receives air tube 63, the interior of this tube being seen at 64, Figure 1. As the fuel (in a vapor state during normal operation) issues from the nozzle port 61, it draws air from the air tube 63 and mixes therewith in the mixing tube 9. The resultant mixture burns within the mantle 5 to heat the same to incandescence.

Impurities in the fuel tend to clog the minute port 61 in the nozzle housing 8. In order to prevent such clogging, the shaft 65 is disposed in the bore 58 and carries a small thin wire 66 which, when inserted in the port 61, cleans the same. At its upper end, the shaft 65 carries cross head 66 which has an opening 67. The end 68 of the rocker shaft indicated generally at 69 fits in this opening to impart up and down movements to the shaft 65 when the rocker shaft is rocked about a horizontal axis.

The handle 70 is pinned to the free end of the rocker shaft 69 as shown and extends at handle 71 to an accessible point for hand operation. When it is desired to clean the port 61, the handle 71 is worked up and down.

The rocker shaft 69 is held in sealed relation to the housing 8 by the ball portion 72 which mates with and receives the cupped inner margin of the washer 73. The washer 73 is held snugly against the ball 72 by the sleeve 75 which is threadedly secured to the housing 55. A resilient washer 74 is sandwiched between the washer 73 and sleeve 75 to maintain a snug seal.

Operation of the lantern is controlled by the handle 76, Figure 2, which is located on the end of the cam shaft 77. This shaft is received in the bore 43 and is somewhat smaller than that bore to permit free flow of the gasoline about the

cam shaft to the port 48. As seen best in Figure 2, the shaft 77 has a pointed end which is received in the corresponding cup shaped seat 78 in the end of the bore 43.

The bore 43 is enlarged at its open end and receives the washer 79 which bottoms on the shoulder formed by the enlargement. A packing sleeve 80 is adjacent the washer 79 and is sandwiched between that washer and the collar 81. The collar seats against the cap 82 which is threadedly received on the extending threaded portion of the housing 38 and at its overhanging end portion 83 engages the collar. The cap 82 is drawn up tight to expand packing 80 and for a fluid tight seal.

The chambers 46 and 47 define annular seats at the points they join their respective ports 44 and 45, these seats being undercut as shown in Figure 2 to define conical seating faces. Valve plungers 84 and 85 are received in these chambers 46 and 47, respectively, and have cupped upper faces which receive the seating washers 87 and 88, respectively. These washers are of deformable material that shapes under the valve closing pressure to fit tightly against the valve seats. Springs 89 and 90 are received in the cup shaped bottom portions of the valves 84 and 85, respectively, and bottom against the end faces of caps 41 and 42 to urge the valve plungers upwardly to seated sealing positions.

Immediately above and in line with the ports 44 and 45, the shaft 77 has eccentric portions as shown in Figures 2 and 3, the eccentric portion aligned with port 44 being indicated at 91 and the eccentric portion aligned with port 45 being indicated at 92. As shown in Figure 3, these eccentric portions define cam surfaces of generally circular conformation located at centers spaced 120 degrees of shaft rotation and extending to the full shaft radius at their points of maximum radius from the shaft axis.

Cam follower pins 93 and 94 are received in the ports 44 and 45, respectively, and extend through openings in the seating washers 87 and 88, respectively, to be received in suitable openings (not shown) in the valve plungers 84 and 85, respectively. These cam follower pins are of such length that when they ride on the point of maximum radius of the corresponding cam, the associated valve plunger is depressed against the bias of the spring 89 or 90 as the case may be to open the valve and permit fluid passage to the port 48. When the cam follower pins 93 and 94 ride on cam points spaced 120 degrees from the positions of maximum radius, they release the valve plungers to seat and form fluid tight seals.

The intake pipe 39 is the intake pipe for normal lantern operation and forms an unobstructed passage from the fluid fuel to the cap 41. The intake pipe 40 operates to produce atomized fuel for starting purposes. This pipe includes a main pipe section 95 which is open to the fuel at its bottom end and carries a loose mass of cotton yarn 96. It is surrounded at its central and upper portions by a spaced jacket tube 97 which has an opening 98 located above the level of fuel in tank 1. Pipe 95 has a similar opening 99 located at a lower point.

When air pressure is created in the tank 1 and the valve plunger 85 opened to define an outlet path through tube 40 to the burner, air is driven through the opening 99 and up through the packing and dislodges fuel particles therein to form a jet of air bearing atomized particles of fuel. When this air reaches the mantle 5, it may be

ignited and burns to create the heat necessary to initial vaporization of the fuel.

The handle 76 has three positions of rest defined by the detent ball 100. Figure 1, which is received in the bore 101 (Figure 4) formed in the extended sleeve portion 102 of the housing 38. The end of this bore is threaded and receives the cap 103 which bottoms against the detent spring 104 which also seats against the ball 100. The ball 100 is thus spring urged into one of the V-shaped grooves 105 formed in the shaft 77 in registry with the bore 101. As shown, these grooves are located at positions spaced 120 degrees from each other and receive the ball 100 to hold the shaft 77 yieldably in one of these three positions, or if it is displaced from such position, to urge the shaft into the nearest position of rest.

From the foregoing it will be evident that the structure shown provides a handle 76 that has three positions of rest defined by the grooves 105 and the spring pressed detent ball 100. In one position, that of Figure 3, the eccentric cam portions 91 and 92 of the shaft 77 release the cam followers 93 and 94 to permit both valve plungers 84 and 85 to close under the bias of their respective springs 89 and 90 to shut off all fuel to the generator 3 and the burner 4. In one position, spaced 120 degrees from this off position and shown in Figure 2, the cam 92 depresses the cam follower 94 against the bias of the spring 90 to open the plunger 85 and permit flow of air carrying atomized fuel into the generator tube 3 and the burner 4. In the third handle position, spaced 120 degrees from the other positions, the cam follower 93 is depressed against the bias of spring 89 to form a direct path of communication from the tube 39 to the generator pipe 3 and the burner 4. In this condition liquid fuel is driven by the pressure in tank 1 into the generator pipe 3 where it vaporizes for normal burner operation.

The above mechanism is particularly desirable in a unit, such as a gasoline lantern, intended for use by unskilled persons. The handle 76 may register with an indicator (not shown) bearing appropriate indicia at the three positions indicating "off," "start," and "normal" operation. The user merely turns the handle to the appropriate position to condition the device for that operation, and it is unnecessary to follow detailed instructions in relation to backing off valves or other operations that are not evident from even a casual inspection of the device.

In accordance with one feature of the present invention, the lantern of Figure 1 is provided with releasable means to lift the globe or chimney 6 to the elevated position shown in the dotted lines of that figure to start the burner. When the chimney is in this elevated position, a match 60 (or other igniting device) may easily be inserted beneath the burner to ignite the issuing fuel and start the burner.

The chimney elevating means consists of a column 106, formed integrally with the nozzle housing 8, which extends upwardly from housing 8 and receives the sleeve 107. The sleeve and housing have mating threads 108 which, when drawn tight, sandwich the central portion 109 of the hood 7 to hold the same in position. In this normal position the sleeve 107 bears against the top of the hood 7 and the shoulder 117 at the bottom of post 106 bears against the bottom of hood 7.

When the sleeve 107 is unscrewed, the hood 7 may be lifted by the bail 114 until the central

portion 109 is just below the threaded portion 108 of column 106. At this point the column forms a shoulder 115. The bail 114 is then rotated to turn the hood and the portion 109 thereof so that when released, it seats on the shoulder 115 to rest in the elevated position shown in Figure 7.

The central portion 109 of the hood 7 is held in the elevated position of Figure 7 by reason of the non-circular shape of the column 106 as seen in Figure 6 and the mating non-circular shape of the opening 116 in hood 7 at portion 109. In the elevated position, the hood is rotated so that the opening 116 does not mate with the column 106 and consequently the hood is suspended from the shoulder 115.

The globe or chimney 6 is sustained from the hood 7 so that if the hood is lifted, the globe is lifted in unison with it. The skirt portion 110 of the hood 7 has a seat defining peripheral indentation 111 which receives the globe support ring 112. The ring 112 has a series of adjacent portions extending between inner and outer radial dimensions and in the seated condition bears against the wall defined by the upper enlarged rim 113 of the globe 6 and the seat 111 to suspend the globe from the hood.

The mantle mounting 10, Figure 1, consists of a flared sleeve having an upper portion 115 of size to be received by the mixing tube 9. The latter tube has a protuberance 116 which receives the mating enlargement 117 of the sleeve 115 to secure the mounting in place. At its lower margin the mantle mounting receives the mantle 5 which is tied thereto in the usual fashion.

While I have shown and described a specific embodiment of the control mechanism of the present invention as applied to a gasoline pressure mantle lantern, it will of course be understood that many modifications and alternative constructions may be made without departing from the spirit and scope of my invention and that the mechanism shown may be applied to other devices such as gasoline pressure stoves. I therefore intend by the appended claims to cover all modifications and alternative constructions coming within the true spirit and scope thereof.

What I claim as new and desire to secure by Letters Patent of the United States is:

1. A three position control mechanism operable to deliver hydrocarbon fuel from a tank to a burner comprising in combination, a housing defining a valve control cavity, means defining a fluid passage from the cavity to the burner, means defining a pair of fluid passages from the cavity extending into the fuel, each of the last passages defining a seating face adjacent the cavity, valves in said passages adapted to seat on the respective faces to close off the passages, spring means operable to urge the valves to seated positions, means associated with one of the last passages operable to atomize fuel passing therethrough, a handle outside the housing having a shaft portion extending into the cavity to points in registry with the last passages, the shaft portion defining cam elements in registry with the last passages, and cam followers extending from said cams to their respective valves, the cams and valves being so constructed and arranged that in one handle position both valves are closed, in a second handle position one is closed and the other opened, and in a third handle position said one valve is opened and the other closed.

2. A three position control mechanism operable to deliver hydrocarbon fuel from a tank to a burner comprising in combination, a housing having a cylindrical bore, means defining a fluid passage from the bore to the burner, means defining a pair of fluid passages from the bore extending into the fuel, each of the last passages defining a seating face adjacent the bore, valves in said passages adapted to seat on the respective faces to close off the passages, spring means operable to urge the valves to seated positions, means associated with one of the last passages operable to atomize fuel passing therethrough, a shaft of smaller diameter than the bore and extending into the bore, the shaft defining cams in registry with the last passages, respectively, and cam followers extending from said cams to the respective valves, the cams and valves being so constructed and arranged that in one position of shaft rotation both valves are closed, in a second position one valve is closed and the other opened, and in a third position said one valve is opened and the other closed.

3. A mechanism to deliver liquid hydrocarbon fuel from a container to a burner of the vapor type comprising in combination, a housing having a cavity, means defining a fuel passage from the cavity to the burner, means defining a pair of fluid passages extending from the cavity into the fuel and each having an enlarged portion spaced from but adjacent to the cavity, valves in the enlarged portions of the last passages, respectively, and adapted to seat on the faces adjacent the cavity to obstruct passage of fuel thereto, springs seated against the valves and the faces of the enlarged portions remote from the cavity operable to urge the valves to seated positions, a control shaft extending into the cavity and defining a pair of cams in registry with the last passages, respectively, and cam followers in the last passages extending from the cams to the valves, respectively, the cams and the cam followers being constructed and arranged so that in one shaft position both valves are released to close, in a second shaft position one valve is retracted against the bias of its spring while the other valve is released and in a third shaft position said other valve is retracted while said one valve is released.

4. In a mechanism to deliver liquid hydrocarbon fuel from a container to a burner of the vapor type comprising in combination, a housing having a cavity, means defining a fuel passage from the cavity to the burner, means defining a pair of fluid passages extending from the cavity into the fuel and each having an enlarged portion spaced from but adjacent to the cavity, valves in the enlarged portions of the last passages, respectively, and adapted to seat on the faces thereof adjacent the cavity to obstruct travel of fuel thereto, springs seated against the valves and the faces of the enlarged portions remote from the cavity operable to urge the valves to seated positions, a control shaft extending into the cavity and having a pair of eccentric cam-defining portions in registry with the last passages, respectively, the eccentric portions being substantially circular in shape and oriented substantially 120 degrees from each other, and cam followers in the last passages seated against the eccentric portions of the shaft and the corresponding valves and operable at the point of maximum radius of each eccentric portion to open the corresponding valve against the bias of its spring.

5. In a mechanism to deliver liquid hydrocarbon fuel from a container to a burner of the vapor type comprising in combination, a housing having a cavity, means defining a fuel passage from the cavity to the burner, means defining a pair of fluid passages extending from the cavity into the fuel and each having an enlarged portion spaced from but adjacent to the cavity, valves in the enlarged portions of the last passages, respectively, and adapted to seat on the faces thereof adjacent the cavity to obstruct travel of fuel thereto, springs seated against the valves and the faces of the enlarged portions remote from the cavity operable to urge the valves to seated positions, a control shaft extending into the cavity and having a pair of eccentric cam-defining portions in registry with the last passages, respectively, the eccentric portions being substantially circular in shape and oriented substantially 120 degrees from each other, and cam followers in the last passages seated against the eccentric portions of the shaft and the corresponding valves and operable at the point of maximum radius of each eccentric portion to open the corresponding valve against the bias of its spring, and detent elements operable yieldably to hold the shaft in position to retract the valves or the aforesaid positions spaced 120 degrees therefrom.

6. A mechanism to deliver liquid hydrocarbon fuel from a container to a burner of the vapor type comprising in combination, a housing having a bore, means defining a fuel passage from the bore to the burner, means defining a pair of fluid passages extending from the bore into the fuel and each having an enlarged portion spaced from but adjacent to the bore, valves in the enlarged portions of the last passages, respectively, and adapted to seat on the faces thereof adja-

cent the bore to prevent travel of fuel thereto, spring seated against the valves and the faces of the enlarged portions remote from the bore operable to urge the valves to seated positions, a control shaft smaller in size than the bore extending into the bore and having a pair of eccentric cam-defining portions in registry with the last passages and an intermediate detent-receiving portion defining three holding points, the eccentric portions of the shaft being rounded in shape and each of the two portions having its point of maximum radius aligned with a corresponding one of the detent holding points, and cam followers in the last passages seated against the eccentric portions of the shaft and the corresponding valves and operable at the point of maximum radius of each eccentric portion to open the corresponding valve against the bias of its spring, and a detent in registry with the detent portion of the shaft yieldably to hold the same in position.
